UNITED STATES PATENT OFFICE.

THOMAS W. JOHNS, OF FLORAL PARK, NEW YORK.

TYPE-SLUG-CASTING MECHANISM.

1,318,877.

Specification of Letters Patent. Patented Oct. 14, 1919.

Application filed July 23, 1918. Serial No. 246,313.

To all whom it may concern:

Be it known that I, THOMAS W. JOHNS, a citizen of the United States, formerly residing at Brooklyn, in the county of Kings and State of New York, but now residing at Floral Park, in the county of Nassau and State of New York, have invented new and useful Improvements in Type-Slug-Casting Mechanism, of which the following is a specification.

This invention relates to improvements in type-casing machines and more especially to those of the linotype class which cast slugs bearing type characters on an edge thereof.

In machines as heretofore constructed, the mechanism for casting the type slugs comprised a metal pot or crucible containing the molten type metal, the crucible containing a cylinder which communicated with a spout through which the type metal was introduced into the mold and a plunger reciprocable in the cylinder to force the type metal therefrom through the spout and into the mold to cast the slug therein. However, it has been found from experience that the return stroke of the plunger, while the spout of the metal pot is still in engagement with the mold, causes the type metal to be drawn back from the cast slug into the throat of the metal pot, this being particularly the case in the casting of relatively large slugs, in consequence of which the cast slug is hollow on its bottom or base.

The primary object of the present invention is to provide novel and improved means whereby drawing of the type metal from the slug back into the throat of the metal pot is avoided, with the result that the slug will contain the full amount of metal and will be solid, the means provided by the present invention for accomplishing this result being relatively simple and inexpensive in its construction and positive and certain in its action, and, furthermore, it is readily applicable to metal pots or crucibles such as those commonly used upon slug or type-casting machines.

In the accompanying drawing:

Figure 1 represents a vertical section taken centrally through a metal pot or crucible and the co-operative mold wheel and mold, the metal pot or crucible embodying the present invention.

Fig. 2 is a view, partly in section and partly in elevation, showing in detail the construction of the metal pot plunger, the parts be-

ing shown in the relative positions they occupy during the descent or metal-injecting stroke of the plunger, and

Fig. 3 represents a central vertical section through the plunger showing the parts thereof in the relative positions they occupy during the ascent or return stroke of the plunger.

Similar parts are designated by the same reference characters in the several views.

The present invention is applicable generally to slug or type-casting machines of the types wherein the type metal is forced or injected into the slug or type mold by a reciprocating plunger. The preferred embodiment of the invention is shown in the present instance as applied to a metal pot such as that commonly used in connection with type-casting machines of the linotype class, but it is to be understood that the invention is not restricted to the precise construction shown as equivalent constructions are contemplated and will be included within the scope of the claims.

In the present instance, 1 represents the mold wheel such as that commonly used upon machines of the linotype class, this mold wheel containing one or more slotted molds 2, the mold when in use being adapted to receive a line of matrices 3 at its forward side in a manner well understood by those familiar with machines of this class. The metal pot or crucible 4 comprises a metal well 5, a cylinder 6, usually arranged vertically within the well, a throat 7 which leads from the bottom of the cylinder upwardly and forwardly into a mouth-piece 8, the latter having orifices through which the type metal passes from the throat and into the cavity of the mold, the forward face of the mouth-piece being flat and adapted to fit closely against the rear face of the mold. In machines of the linotype class, the metal pot is movable forwardly or rearwardly; that is to say, toward and from the mold disk, the metal pot moving forward to bring the mouth-piece 8 thereon against the rear face of the mold preparatory to the injection of the type metal into the mold, and after the slug has been cast in the mold the metal pot recedes, separating the mouth-piece 8 from the mold. Injection of metal into the mold is effected by a plunger 9 which reciprocates in the cylinder 6, reciprocation of the plunger being usually effected by a cam-controlled link or

connecting rod 10. Molten type metal from the well 3 is supplied to the under side of the plunger through a suitable port 11 which is uncovered when the plunger is retracted or elevated, this port being closed during the descent or the metal injecting stroke of the plunger. The metal pot is usually inclosed by a casing 12 and a gas or other burner or heater is provided in the opening 13 in the bottom of this casing to maintain the type metal in the metal pot in a molten condition.

According to the present invention, the plunger 9 is provided with a port or passage 14 which extends through the bottom thereof, thus establishing communication between the upper and lower sides of the plunger. A counterbore or valve seat 15 is formed around the upper end of this passage. The actuating link or connecting rod 10 is provided with an elongated opening 16 to receive the wrist pin 17 which connects the plunger to the link 10, and the link 10 is formed with a tapered or other suitably shaped extension 18 which is adapted to fit the seat 15 surrounding the upper end of the port or passage 14.

In the operation of a metal pot embodying the present invention, the initial part of the down stroke of the plunger-actuating link or member 10 brings the extension 18 thereon into engagement with the seat 15 surrounding the port or passage 14, thus closing this port or passage 14 preliminarily to the descent of the plunger. Continued descent of the actuating link or member 10 causes the metal in the cylinder beneath the plunger to be forced through the throat 7 and the orifices in the mouth-piece 8 into the cavity of the mold, thus filling the latter with the necessary amount of type metal to cast the slug. The initial part of the return movement or up stroke of the actuating member 10, which occurs in machines of this class while the mouth-piece 8 is still in engagement with the mold, withdraws the extension 18 from the seat 15, thereby uncovering or opening the port or passage 14, and the following ascent of the plunger causes metal to flow from the upper side of the plunger through the port or passage 14 to the under side of the plunger and the metal so passed through the plunger is sufficient to prevent the creation of a vacuum in the throat 7, which vacuum heretofore has caused type metal to be withdrawn from the mold. In consequence, the full amount of type metal will remain in the mold, although the port or passage 14 is sufficiently reduced to enable the return stroke of the plunger to draw the metal away from the mouth-piece.

The present invention provides means, which acts positively and with certainty, to avoid the creation of a vacuum in the body

of metal between the plunger and mold, and hence suction tending to draw part of the molten metal out of the mold incident to upward movement of the plunger. The type slugs in consequence will be solid and the production of slugs deficient in type metal, especially in slugs of the larger sizes, is avoided. By providing a vent through the plunger, which vent is controlled by the mechanical operating connection for the plunger, certainty in operation is insured, and, furthermore, the invention is thus rendered capable of application with facility to metal pots or crucibles such as those commonly used in connection with the different types of typographical machines for casting types or slugs.

I claim as my invention:

1. A metal pot or crucible for typographical machines comprising a spout, a plunger for forcing type metal therethrough into a mold, means for admitting such metal to the forward side of the plunger, means for actuating the plunger on its working and return strokes, and means controlled mechanically by said actuating means for preventing the creation of a vacuum in said spout incident to the return stroke of the plunger. 85

2. A metal pot or crucible for typographical machines comprising a spout, a reciprocating plunger for forcing metal through said spout and into a mold, means for admitting such metal to the pressure side of the plunger while the latter is retracted, actuating means for causing reciprocation of the plunger, and means operative mechanically by said actuating means for preventing the creation of a vacuum in said spout during the return stroke of the plunger. 95 100

3. A metal pot or crucible for typographical machines comprising a spout, a cylinder communicating with the spout, a plunger in said cylinder for forcing type metal into a mold, the cylinder having a port which is uncovered by the plunger when the latter is retracted to admit type metal to the pressure side of the plunger, actuating means for reciprocating the plunger, and means operative mechanically by said actuating means, during the initial part of its movement to effect the return stroke of the plunger and while said port is closed, for preventing the creation of a vacuum in said spout during such return stroke of the plunger. 110 115

4. A metal pot or crucible for typographical machines comprising a spout, a cylinder communicating therewith, a plunger reciprocable in said cylinder for forcing type metal into a mold, the cylinder having a port which is opened to admit type metal to the pressure side of the plunger during the latter portion of the return stroke of the plunger, actuating means for effecting the working and return strokes of the plunger, and means controlled mechanically by 120 125 130

said actuating means for admitting metal to the spout incident to the commencement of the return stroke of the plunger and while the said port is closed.

- 5 5. A metal pot or crucible for typographical machines comprising a spout, a plunger for forcing type metal therethrough into a mold, said plunger having a vent passage leading to its pressure face, means for admitting such metal to the pressure face of the plunger while the latter is substantially in its retracted position, actuating means for operating the plunger on its working and return strokes, and means operative by 10 said actuating means to close said passage preparatory to the working stroke and to open said passage preparatory to the return stroke of the plunger.
6. A metal pot or crucible for typographical machines comprising a spout, a reciprocable plunger for forcing metal therethrough into a mold, said plunger having a 15
- 20

passage extending through its head from its rear to its forward side and formed with a valve seat, means independent of said passage and controlled by the plunger for admitting a supply of type metal to the spout only when the plunger is retracted, and a reciprocatory actuating member for operating the plunger on its working stroke, 25 said member having a lost motion connection with the plunger and also having a portion adapted to engage in and disengage from said valve seat to respectively close and open said passage preparatory to the working and return strokes of the plunger.

In testimony whereof I have hereunto set my hand in presence of two subscribing witnesses.

THOMAS W. JOHNS.
